SAFE

Filed Aug. 3, 1928

UNITED STATES PATENT OFFICE

HARRY B. CHAMBERLAIN, OF KALAMAZOO, MICHIGAN

SAFE

Application filed August 3, 1928. Serial No. 297,170.

The main objects of this invention are:

First, to provide a wall safe that is very simple in construction.

Second, to provide a supporting means that 5 may be a part of the wall or may be a means remote therefrom as a post.

Third, to provide a series of locks with different keys to prevent the opening of the safe by a single person.

10 Objects pertaining to details and economies of construction will appear from the description to follow.

A preferred embodiment of my invention is illustrated in the accompanying drawings, 15 in which:

Fig. 1 is a perspective view of my improved safe mounted on the wall.

Fig. 2 is a horizontal section taken on line 20 2-2 of Fig. 1, showing mainly the method of securing the safe to the wall.

Fig. 3 is a vertical section taken on line 3-3 of Fig. 1, the supporting means shown as being embedded in the wall.

Fig. 4 is a rear perspective view with parts 25 broken away to more clearly show the locking means.

Fig. 5 is a partial section taken on line 5-5 of Fig. 2, showing mainly the reinforcing means for the locking bolts.

30 Referring to the drawings, 1 is my improved safe. 2, 2 are the separated retaining bolts. 3 is a channel bar support embedded in the wall and floor, see Fig. 3. 4 is a recess in which the channel bar 3 is secured. 35 31 is a short channel bar with upturned ends embracing the bolt heads and holding them against rotation, being disposed within the channel bar 3.

5 is the door of the safe, being of the circular type. 51 is the supporting hinge therefor, which is used only to support the door when it is in open position. 52 is a projecting lock lug cast integral with the door, which retains the door in place when closed and locked, so 45 that breaking the hinge is not sufficient to open the safe.

6, 6 are a pair of bolt locks provided with bolts 61, 62, and having separate and different keys 63, 64. 7 is a projecting T-shaped lug 50 cast integral with the door, and 71, 71 are the

arms thereof partially embracing the locking bolts and protecting the same. 8 is a lug cast integral with the inner wall of the safe, having an inclined face 81 to protect the ends of the bolts from being exposed by drilling. 9 is 55 a projecting post cast integral with the rear wall of the safe and abutting the rear of the lock to prevent the lock being driven in from the front. 10 is an elongated slot for the insertion of money. 60

A pair of locks 6 with different keys are used for a special purpose, as, for example, in a gasoline station, where each of the attendants may carry a different key for the locks and the only time the safe can be opened is 65 when both keys are available.

Having thus described my invention, what I claim as new and desire to secure by Letters Patent is:

1. In a wall safe, the combination of an integral cast box recessed at its back, a vertical channel bar disposed in said recess, and bolts projecting inwardly therethrough with nuts at their inner ends for attaching said box, as specified. 70

2. In a safe, the combination of a cast body with flanged doorway, a flanged door with inwardly-projecting lug for engaging the side of the doorway, a bolt lock therefor, and a protecting lug for the bolt with a 80 beveled surface oblique to the axis of the bolt, as specified.

3. In a wall safe, the combination of the safe with a suitable lock thereon, and a post projecting from the back of the safe into 85 proximity to the lock to support the same and prevent its being driven in, as specified.

4. In a wall safe, the combination of an integral cast box recessed at its back, supports comprising a vertical channel bar disposed in said recess, bolts projecting inwardly therethrough with nuts at their inner ends for attaching said box, and a locking channel bar embracing the bolt heads and disposed within the main channel, the said supports being embedded in the wall, as specified. 90

In witness whereof I have hereunto set my hand.

HARRY B. CHAMBERLAIN. 100
